UNITED STATES PATENT OFFICE.

HARRY E. NORVIEL, OF ANDERSON, INDIANA, ASSIGNOR TO DELCO-REMY CORPORATION, OF DAYTON, OHIO, A CORPORATION OF DELAWARE.

LOCK SWITCH.

Application filed June 13, 1927. Serial No. 198,331.

- This invention relates to electric switches and particularly to a switch adapted for use in connection with ignition apparatus disclosed in the copending application of J. L. 5 Arthur, Serial No. 198,682 filed June 13, 1927. The Arthur ignition apparatus comprises an ignition coil having two primary windings which are connected by a suitable switch either in parallel with a storage battery or 10 other current source or in series therewith. This apparatus can be used advantageously in the electrical system of an automobile in which a storage battery, charged by a generator driven by the automobile engine, is used 15 to supply current during the cranking of the engine to the ignition apparatus, and generally to the starting apparatus where an electric starter is used. In cases where the battery is partly discharged or the starting apparatus considerably drains the battery, thus 20 reducing its voltage substantially below normal, sufficient ignition coil energy can be obtained for ignition purposes while cranking if the ignition primary windings are connected in parallel with the battery in order to reduce the total resistance of the ignition primary circuit. Where ignition current is supplied by a generator at normal voltage during 25 the running of the engine, the primary windings should be connected in series in order to increase the resistance of the primary circuit and prevent an abnormal flow of current through the ignition coil while the engine is running. Therefore the switch which 30 controls the ignition circuit has in addition to the "off" position, a "start" position in which the primary windings are connected in parallel, and a "run" position in which the windings are connected in series with the battery. 35 One of the objects of the present invention is to provide an improved switch for controlling the ignition apparatus of the Arthur application referred to. More particularly it is an object to provide a switch requiring the 40 use of a key to unlock the switch so that it can be moved from "off" position to either the "start" or "run" position, the key providing a handle for turning the movable contact of the switch; and to provide a switch in which 45 a spring is employed for moving the switch operating member from its "start" to "run" position automatically when the key or switch handle is released. This feature provides for automatically reducing the current 50 in the primary circuit of the ignition system in case the operator should fail to turn the switch to "run" position after the engine becomes self-operative. 55 Further objects and advantages of the present invention will be apparent from the following description, reference being had to the accompanying drawings, wherein a preferred embodiment of one form of the present invention is clearly shown. 60 In the drawings: 65 Fig. 1 is a front view of a switch and coil assembly unit embodying the present invention. Fig. 2 is a longitudinal sectional view thereof on the line 2—2 of Fig. 1. 70 Fig. 3 is a fragmentary sectional view on the line 3—3 of Fig. 1. Fig. 4 is a fragmentary view on the line 4—4 of Fig. 2. 75 Figs. 5, 6 and 7 are wiring diagrams illustrating the use of the present invention. The ignition apparatus with which the present switch is particularly adapted to be used, will first be described with reference to Figs. 5, 6 and 7. The ignition coil has two 80 primary windings 20 and 21 which are inductively related to a secondary winding 22. Winding 20 is connected by wire 23 with a switch contact 24 and by wire 25 with a terminal 26 which is connected with an ignition 85 timer 27 grounded at 28. The winding 20 is also connected by wire 29 with a switch contact 30. The winding 21 is connected by a wire 31 with a switch contact 32 and by a wire 33 with a contact 34, and also by wire 35 with a terminal 36 to which one end of the secondary 90 22 is connected. Terminal 36 is connected with a battery 37 grounded at 38. The other end of the secondary 22 is connected with an ignition distributor 39. 95 The switch includes movable arcuate contacts 40 and 41 which are represented by dot and dash lines in Figs. 5, 6 and 7. When the contacts 40 and 41 are in the position shown in Fig. 5, the ignition circuit will be interrupted, the switch being in the "off" position. When the contacts 40 and 41 are turned in the position shown in Fig. 6, known as the "start" position of the switch or the position occupied by it during the cranking of the engine, 100 the primary windings 20 and 21 will be connected in parallel with the battery. The arrows 42 in Fig. 6 designate the direction of current flow so that these parallel circuits may be clearly apparent. After the engine 105 110

has become self-operative, the ignition switch may be turned to "on" position in order to move the contacts 40 and 41 into the position shown in Fig. 7. Then the switch connects the primary windings 20 and 21 in series with the battery to increase the resistance of the primary circuit and to reduce the current therein to normal value. The series connection of the windings 20 and 21 is clearly indicated by the arrows 43 in Fig. 7. It will be noted that the connections are so made that the coils 20 and 21 also act cumulatively regardless of how they are connected with the battery.

As shown structurally in Fig. 2, the coils 20, 21 and 22 surround a core 50, the ends of which are supported within recesses provided by non-conducting bodies 51 and 52 located centrally within a metal case 53. The body 52 is embedded in insulating compound 54 within the case 53, this compound having been poured while molten into the case before an end cover 55 of insulating material is inserted within the case 53. The member 52 includes a cable-receiving sleeve 56 which extends centrally through a metal end cover 57 having its flange 58 formed over the flange 59 of the case 53. The body 52 insulatingly supports the terminals 26 and 36. The sleeve 56 is provided with a metal lining 60 electrically connected by a pin 61 with the core 50 upon which the inside turn of the secondary 22 is grounded by the lead 62. The sleeve 60 is connected with the distributor 39. Number 63 designates insulating compound which is poured while molten into the case 53 before the cover 57 and body 52 are assembled therewith.

The external magnetic circuit of the coil is provided by several turns of sheet iron 65 insulated by several turns of paper 66. This material is wrapped around the assembly of windings and core before this assembly is placed in the case 53.

The switch for controlling the circuits of the ignition coil is housed within a case provided by the case cover 55 which forms the base of the switch and a tubular extension 53^a of the case. The base 55 is secured to the case by spinning into the case two annular grooves 67 to form on the inside of the case two annular ridges 68 between which the base 55 is confined. The front wall of the switch is provided by the frame member 70 which is retained by the case 53^a by bending a flange thereof at 71 against a shoulder 72 provided by the frame 70. In this way the frame 70 is clamped against a spacing tube 73 located between the frame and the switch base 55.

The frame 70 supports a key shaft 74 to which is attached by screws 75 a non-conducting contact carrier 76 which supports the segmental contacts 40 and 41. The stationary contacts 24, 32, 30 and 34 are secured to the base 55 by hollow rivets 24^a, 32^a, 30^a and 34^a,

respectively. The bearing boss 77 which supports the key shaft 74 is surrounded by coil spring 78, one end of which bears against a boss 79 provided by the frame 70 and the other end of which is received by a hole 80 in a detent plate 81 driven by the shaft 74. The spring 78 is biased for rotating the contact carrier in a clockwise direction as viewed in Figs. 1, 5, 6 and 7 and resists movement of the carrier in a counterclockwise direction from the "run" position into the "off" position or the "start" position. The plate 81 is provided with an arcuate notch 82 which receives a lug 83 provided by the bearing boss 77 in order to limit movement of the contact carrier in either direction. The plate 81 is provided with a hole 84 which is received by a portion of a ball 85 guided by a recess 86 in the boss 79 and urged by a spring 87 against the plate 81.

The key shaft 74 carries a number of locking bars 90 which when the key 91 is not in the lock will move into one of the longitudinal grooves 92 provided in the wall of the bearing boss 77. The ends of the locking bars 90 are adjacent the grooves 92 only in the "off" position of the key shaft 74. Therefore when the key 91 is removed, the shaft will be retained in "off" position by the bars 90 against a torsion of the spring 78. Before starting the engine, the key 91 is inserted in the key shaft and the key is turned into "start" position and is manually held there. After the engine becomes self-operative and supplies ignition current through an engine driven generator at normal voltage, the key 91 may be released to permit the spring 78 to turn the contact carrier into the "run" position, or the key may be turned by the operator into this position. But if the operator should forget to turn the switch to "run" position, this operation will be accomplished by the spring 78. In the "run" and "start" positions of the lock the key cannot be removed. Before the switch can be turned off the key must be

grasped by the hand of the operator and turned in "off" position. The switch will not remain in "off" position if the key is released in "off" position without being removed from the lock, since the spring 78 will return the key to the "run" position. Therefore the operator must pull the key from the lock after it has been moved to "off" position. This requires at least a partial withdrawal of the key from the lock in order to retain the switch in "off" position. Quite naturally the driver will remember to remove the key entirely if he is required to partially remove the key in order that the switch will remain in "off" position.

From the foregoing it is apparent that my improved switch provides first, for switching the circuits of the two primary windings of an ignition coil from parallel to series automatically so that the ignition coil will not be

damaged by an excessive flow of current if the operator should forget to turn the key from "start" to "run" position; and secondly the switch requires a manipulation which is helpful in reminding the operator that the key should be removed from the lock when the ignition is turned off.

While the form of embodiment of the present invention as herein disclosed, constitutes a preferred form, it is to be understood that other forms might be adopted, all coming within the scope of the claims which follow.

What is claimed is as follows:

1. Ignition apparatus comprising, a coil having two primary windings, a switch having an "off" position of its operating member in which position the windings are disconnected, a "start" position in which the windings are connected in parallel and a "run" position in which the windings are connected in series, means for locking the switch operating member in the "off" position only, and a spring for moving the operating member from the "start" to the "run" position.
2. Ignition apparatus comprising, a coil having two primary windings, a switch including movable contacts having an "off" position in which the windings are disconnected, a "start" position in which the windings are connected in parallel, and a "run" position in which the windings are connected in series, a removable operating handle for moving said contacts, a spring for moving the contacts from "start" to "run" position, and means providing for removal of the handle from the switch only in the "off" position thereof and for locking the switch movable contacts in this position by the removal of the handle.
3. A switch including movable contacts for turning off an ignition circuit and having a "start" position in which the ignition circuit is arranged for providing ignition during engine cranking, and having a "run" position in which the ignition circuit is arranged for engine running, a key controlled member for moving the movable contacts of the switch from "off" to "start" or "run" positions, a spring for moving the member from

"start" to "run" position when the operator releases the key in "start" position, and means providing for removal of the key only in the "off" position of said member and for locking said member in "off" position by removal of the key.

4. A switch according to claim 3 in which the "off" position of the key controlled member is between the "start" and "run" positions so that the key must be moved to "off" position and moved out from the member in order to retain the member in "off" position.

5. A switch including movable contacts for turning off an ignition circuit and having a "start" position in which the ignition circuit is arranged for providing ignition during engine cranking, and having a "run" position in which the ignition circuit is rearranged for engine running, a removable handle for the switch, a spring resisting movement of the movable contacts of the switch from "run" to "off" position, and means for holding the switch contacts in "off" position when the handle is removed.

6. An electric switch having a member movable between "off" and "on" positions, a handle attachable to and detachable from the movable member only in the "off" position, means locking the switch member in the "off" position when the handle is removed, and a spring resisting movement of the switch member into "off" position whereby the switch member will not remain in "off" position unless the handle is removed.

7. An electric switch having a member movable between "off" and "on" positions, an operating key attachable to and detachable from the movable member only in the "off" position, means co-operating with the key for locking the switch member in the "off" position when the key is removed, and a spring resisting movement of the switch member in "off" position whereby the switch member will not remain in "off" position unless the key is removed.

In testimony whereof I hereto affix my signature.

HARRY E. NORVIEL.
